UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK

TELEPHONE-EXCHANGE SYSTEM.

1,109,618.

Specification of Letters Patent.

Patented Sept. 1, 1914.

Application filed July 20, 1906. Serial No. 327,096.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems and has for its object the improvement of such systems in the manner which will hereinafter appear.

It is my desire in the present invention to 15 produce a semi-automatic telephone exchange outfit in which the amount of connective apparatus will be substantially less than that of subscribers' apparatus, and its control rendered more certain than heretofore possible.

The invention may be briefly outlined as follows: a number of connective trunks approximately 10 per cent. of the number of lines, is provided, with terminal connections 20 such that a calling line will be automatically switched to an idle trunk, such trunk terminating in automatic selecting apparatus and having associated with it certain relays which pass under the control of the subscribers during connection. To work the 25 automatic selecting apparatus, I provide operators who have automatic switching means for connecting them to the trunks when lines are calling but at no other time. Each operator 30 has control of one or more sending or impulse transmitting devices whereby suitable impulses may be applied to the automatic selecting apparatus to produce any desired connection. A very important feature 35 of the invention lies in this sending apparatus, the arrangement of which enables me to use one common commutator or circuit breaker for an entire exchange. All the operators' sending wheels run synchronously 40 with this commutator, and instead of having each wheel provided with a certain number of teeth to make and break the circuit, I provide each wheel with one unbroken tooth of sufficient length to take in the required 45 number of impulses from the main commutator. Thus, the number 1 wheel has a very short tooth which corresponds to one tooth on the main commutator; the number 2 wheel has a tooth equal in length to two 50 teeth on the commutator, and so on. The 55 teeth on the commutator and so on.

thermore, there is no sparking at the contacts on the wheels, all makes and breaks being at the main commutator, for the reason that the make and break at each individual number wheel occurs a little before 60 or a little after the corresponding make or break on the main commutator. Thus, for example, suppose the number "3" is to be transmitted, and the circuit of the number 3 wheel is therefore closed, the tooth on this 65 wheel comes into contact with its spring pen during the interval of break on the main commutator, and remains in contact long enough for the main commutator to make and break three times, passing off of its individual spring during the third break of 70 the main commutator. Thus it will be observed that all deterioration due to sparking and the kick of coils in the circuits is confined to the main commutator which I construct very solidly, preferably with compressed mica insulation and a carbon faced or solid carbon brush.

For the sake of convenience I shall illustrate and describe in this case selector and 80 connector switches of the type known as the Strowger, such switches being well illustrated in the Letters Patent No. 815,176 and No. 815,321, issued March 13, 1906 to Automatic Electric Company as the assignee of 85 Keith and Erickson. The primary selector and operators' trunk selecting switches may be of the same general type, at least in so far as regards their contacts and the way their contact arms and banks are arranged. In 90 one particular there is a difference because my primary selector switches for answering calls do not have any vertical motion but simply rotate. Another point of difference is that I prefer to use a power drive with a 95 clutch for each individual switch, although this is not material, and a step by step movement, preferably driven from the main commutator and similar in every respect to the 100 rotating movement of the patented switches referred to, may be employed.

My invention is illustrated in the accompanying drawings wherein--

Figure 1 shows a subscriber's station with its contacts terminating in a primary switch connected to a trunk circuit; and also a secondary outfit connected to a rotating or secondary switch which picks out a calling trunk. Fig. 2 shows a set of signaling buttons and an impulse generator to work in 110

connection with Fig. 1. Fig. 3 shows the circuits of an automatic switch. Fig. 4 is a modification of Fig. 1 wherein the primary switch is connected directly to the line. Fig. 5 is still another modification showing the primary switch connected to the line and the secondary switch connected to the trunk.

Referring now to Fig. 1, the subscriber's station A comprises apparatus usual in common battery systems consisting of the transmitter, receiver, ringers, condenser and switch-hook. The line wires from this station terminate in the line relay M through the normally closed contacts of the cut-off relay M'. The relay M when energized places battery on the contact z^{60} in the bank of the switch Z. This switch when not busy is constantly rotating, being normally connected to a constantly rotating shaft by means of a friction clutch z^{13} engaging the clutch z^{15} which is rigidly fastened to the shaft. This clutch is controlled by the magnet D^{20} which when energized attracts the arm d^{20} , disengaging the clutch z^{15} thus causing the spindle Z' carrying the wipers to come to rest. This magnet D^{20} is energized when the test wiper z^{50} rests on the test contact z^{60} and the line 1-2 is calling and holding relay M energized. The trunk wipers z^{40} and z^{50} are disconnected from the trunk wires 30 and 31 respectively by the normally open contacts of the relay D^{10} . This relay is energized in multiple with the magnet D^{20} and is held energized by the action of the relay D when the trunk is connected to the calling line. The relay D connected to the grounded side of battery is tapped to the tip side of the trunk 30 while the relay D' connected to the free side of battery is tapped to the sleeve side of the trunk 31, thus furnishing battery to the calling subscriber. The relay E is the starting relay and is operated when the talking trunk is connected to a secondary trunk shown in the lower portion of the drawing. This relay when energized locks itself through the contacts e^3 and e^4 and is thereafter controlled by the relay D through the contacts d^5 and d^6 . The relays S and S' respectively, each have one terminal connected to the contacts z^{40} and z^{50} in the secondary switch Z'. The relay S' has its other terminal connected to the free side of battery. The relay S which responds to impulses from the sending machine shown in Fig. 2, repeats these impulses over the tip side of the trunk 30 to the switching mechanism in Fig. 3. The relays S and S' also furnish battery for the operator's set in the secondary outfit and at the same time connect her talking set to the trunk wires enabling her to converse with the calling subscriber.

The secondary switch Z' is identical with that of Z and its magnet D^{20} is energized

by the action of the relay D' in the same manner that the magnet D^{20} is energized by the action of the relay M. The relay D^{40} is connected in multiple with the magnet D^{20} . The relay T in the secondary outfit is provided with a make before break contact and through this contact is connected to the wiper z^{55} , when the relay D^{40} is operated. When the switch Z' comes to rest with its wipers in connection with contacts leading to the talking trunk, the relays T and S are connected in series. The relay T becoming energized locks itself through the contacts t and t' opening the contact t' thus disconnecting itself from the wiper z^{55} and taking battery off of relay S. The action of the relay S closes the contacts s and s' thereby completing the circuit of the relay E which remains locked through the contacts e^3 and e^4 and under control of the relay D'. Ground is placed on the test contact z^{50} over the wire 18 when the relay D' is energized upon being connected to the line and is removed by operation of relay E. The operation of the relay T closes the circuit of the lamp L which is the signal to the operator that there is a call. The relay H has its circuit closed when the operator depresses the starting button $K^{x'}$ in Fig. 2. This relay in turn closes the circuit of the relay H' which in turn closes the circuit of the motor in Fig. 2. After the operator releases the button $K^{x'}$ the circuit of the relay H is maintained through the pen g^6 which then rests on the metal portion of the wheel Q^{25} , the metal portion being connected to battery. The circuit of the relay T is normally completed through the contacts h^{10} and h^9 of the relay H', but after this relay is energized the circuit is maintained through the contacts h^2 and h^3 of the relay H.

Referring now to Fig. 2 a very important feature of this invention is shown wherein a common impulse generator supplies the entire exchange. Individual selector wheels having teeth of different lengths are provided. These teeth are so proportioned and the wheels so run relatively to the main commutator that they will always make and break a little before and a little after the circuit at the commutator is made and broken respectively, which positively avoids sparking at the contact pens. This arrangement is shown diagrammatically in Fig. 2 wherein I have illustrated the main commutator, one set of number wheels, an electric motor for driving the shaft common to all of these, and a set of operator's buttons similar to those used in selective ringing systems in a great many exchanges. Any type of button can be used provided that when one button is depressed it must be kept locked or in an indicating position until some other button is depressed whereupon the first button must be released and

assume its normal position. In the accompanying drawing I have shown these individual wheels being driven by a motor which starts up when the operator depresses the 5 starting button. In place of the motor I may have the same operated by a magnetically controlled friction clutch which when operated by the operator pressing the starting button connects them to a constantly 10 rotating shaft. The wheels, Q^1 , Q^2 , Q^3 , Q^4 , and Q^5 are provided with teeth of different lengths, the tooth on wheel Q^1 being the shortest while that of Q^5 is the longest. The tooth of the wheel of Q^1 in passing over 15 a contact pen transmits one impulse through the medium of the common commutator Q^{10} . The tooth of the wheel Q^5 in passing over one of these pens transmits five impulses through the same medium. A complete machine will have ten of these wheels so that 20 any digit from one to ten can be indicated by sending the appropriate number of impulses. In the drawing in order to economize space and avoid confusion, I show only 25 the first five wheels. In practice these wheels are all one, the teeth being formed upon the surface of a drum which can be driven by a suitable motor or shaft. The speed which I have found most suitable for 30 this device and for the type of switches I here illustrate is approximately twelve revolutions per minute. For a 100 line exchange which I am illustrating the first four wheels will be provided with three pens and the remaining six provided with two pens each. 35 These pens through which the impulses are transmitted are connected in their proper order to the buttons K^1 , K^2 and K^3 . The pen q^1 is connected to the individual spring 40 71 of the key k^1 in the set K^1 by means of the wire 74. Similarly the pen q^2 of the wheel Q^2 is connected to the spring 71 of the key k^2 of the set K^1 by the wire 75, and so on. The succeeding wires of all the pens q^2 45 go to the individual springs of the keys of the set K^1 . The second set of springs g^2 are connected in the same order to the individual springs of the keys belonging to the set K^2 ; the third set of springs g^3 are similarly 50 connected to the individual springs of the key set K^3 . The layout in this figure is intended for an exchange of one hundred lines or less, the two sets of keys K^1 and K^2 serving to control two sets of number wheels 55 for selective purposes while the third set of keys K^3 is intended in the present case for selective ringing on party lines.

The wheel Q containing the three teeth transmits what is commonly called the rotary 60 impulses to affect the side switch mechanism in the connector switch. The impulses from this wheel instead of being controlled by battery through the medium of the commutator Q^{10} sends grounded impulses operated 65 directly by the teeth coming in contact with

a single pen. The wheel Q^{25} has an insulated point upon which the contact spring q^6 normally rests. If this wheel is started by the operation of the motor the pen q^6 riding on the metal portion of the wheel 70 closes the circuit of the motor which will continue to run until the wheel Q^{25} has made one complete revolution and the pen q^6 again rests on the insulated portion. The teeth on the wheel Q are so set that they 75 come successively in contact with the pen q^6 immediately after the teeth of the impulse wheels have ceased sending their respective impulses.

The common springs 78 of the key set are 80 connected together to a common wire 79. This common wire carries to the switches in proper sequence the actuating impulses.

To illustrate clearly the operation of this device, suppose it be desired to transmit 85 over the wire 79 the number 432. The operator depresses the fourth key in the first set and the third key in the second set, and finally the third key in the third set. Thus the spring q^1 of the wheel Q^1 becomes connected to the wire 79; the spring q^2 of the wheel Q^2 becomes connected through its wire to the wire 79. Now as the drum or the wheels rotate what happens is this: First, four impulses from the wheel Q^1 , 90 then a single impulse from the wheel Q^2 , then three impulses from the wheel Q^3 ; then one impulse from the wheel Q ; then three impulses from the wheel Q^4 , and finally a single impulse from the wheel Q , 95 so completing the signal. Any one familiar with the Strowger system of switches will at once perceive that the wires 79 and 82 can be connected directly to the vertical and the rotary side of a switch trunk, respectively, and the impulses will then serve to operate the switches perfectly. I may here state that the sole function of the wheel Q^{25} with its wiper q^6 is simply to send in one complete set of impulses and then stop. 100 Obviously, if the operator sets up the signal keys and the impulses were permitted to go directly into the switch circuits without any starting point, great confusion would result. For this reason I have the various signal 105 wheels always come to rest at a normal starting point which is controlled directly by the wheel Q^{25} and the pen q^6 .

The circuits of Fig. 2 thus described are particularly adapted to operate with the 110 trunk circuit shown in Fig. 3.

Referring now to Fig. 3 the connector switch consists of the vertical relay V which responding to impulses over the vertical side of the trunk operates the vertical magnet 115 V^2 which in turn causes the spindle Z carrying the wipers z' and z to step up vertically. The relay V' connected to the rotary side of the trunk responds to rotary 120 impulses and operates the private relay U 130

which in turn causes the mechanically operated side switches to move one point, disconnecting the vertical magnet V^2 and in its place connecting the rotary magnet V^3 , 5 and at the same time through the side switch w^6 connects the tip side of the trunk to a contact in the private relay which, when closed, connects the test relay J' . The relay D responding to a second set of impulses over the vertical side of the trunk operates the rotary magnet V^3 causing the spindle Z to rotate and bring the wipers to rest on contacts leading to the desired line. The next rotary impulse coming in 10 operates the private relay U in the same manner as before, causing the side switches to make still another movement. This last movement of the side switches disconnects the rotary magnet and in its place connects the relay R' which, when operated, closes the circuit of the locking relay X' which completes the circuit of the ringing relay Y . The relay R' is now in position to be controlled by the third set of impulses coming in over the vertical side of the trunk. This relay controls a set of relays W and these relays in turn control generator current of different frequencies or polarities. All of these relays are self-locking and 15 have a common wire controlling their locking circuits. This common wire, 150, leads to a normally open contact in the relay X' . This relay becoming energized at the first impulse of the third set places battery on this wire. The relay R' is also energized at this juncture and after the first impulse its armature drops back and closes the circuit of the relay W^4 through the normally closed contacts of the relay W^5 . The next 20 impulse operating the relay R' closes the circuit of the relay W^5 through the contacts of the relay W^4 and the normally closed contacts of the relay W^6 , and after the second impulse the circuit contacts of the relay W^6 are closed through the contacts of the relay W^5 . At the third impulse the circuit of the relay W^7 is closed through the contacts of the relays W^4 and W^6 and the normally closed contacts of the relay W^8 ; at the end of the third impulse the circuit of the relay W^8 is closed through the contacts of the relays W^5 and W^7 and the normally closed contacts of the relay W^9 . At the fourth impulse the circuit of the relay W^9 is closed through the contacts of the relays W^4 , W^6 and W^8 . It will be seen from the foregoing description that I have a set of step by step relays controlled by the relay R' , the first relay of the set 25 becoming energized when the relay R' becomes deenergized, the second relay becomes energized when the relay R' becomes energized the second time, and the third relay becoming energized when the relay R' again becomes energized, and so on. 30

This system of relays can be carried on indefinitely. The relay W^6 becoming energized disconnects generator G^1 and in its place connects the generator G^2 to a contact in the ringing relay Y , and the relay W^7 becoming energized disconnects the generator G^2 and in its place connects the generator G^3 and the relay W^8 becoming energized disconnects the generator G^3 , and in its place connects generator G^4 . 35

Battery is supplied to the called subscriber through the relay R and retardation coil I which are normally connected to the calling end of the trunk. The locking circuit of the relay X' is controlled jointly by the normally closed contacts of the relay R and the normally open contacts z^3 and z^2 controlled by the spindle Z . If the called subscriber answers, the relay R becomes energized, disconnecting the relay X' which in turn cuts off the ringing relay Y . If the called subscriber does not answer, the relay X' is disconnected when the calling subscriber hangs up his telephone disconnecting the switch Z which upon returning to its normal position opens the contact springs z^2 and z^3 . The calling subscriber at the end of the conversation automatically places battery on both sides of the trunk circuit operating the relays V and V' simultaneously, the action of which closes the circuit of the test relay J' which in turn closes the circuit of the release magnet J . Battery is placed on both sides of the trunk circuit by the combination of relays in the talking circuit as follows: During conversation the relays D , D' and E remain energized. When the subscriber hangs up his receiver the relay D is the first to fall back or become deenergized which places battery through its normally closed contacts to the contacts in the relay E and from there to the trunk circuit. The next relay to drop back or to become deenergized is the relay D' which is kept energized longer than the relay D on account of being in series with the line cut-off relay through the primary selector sets. After the relay D' becomes deenergized the relay E is disconnected and thus battery is removed from both sides of the trunk. 40

Referring now to Fig. 4 instead of providing each trunk with a primary switch I connect one of these switches to each line and instead of being constantly rotated, it is normally at a standstill and only starts to rotate when the subscriber closes the line circuit by removing his receiver. These switches contain contacts leading to talking trunks. When the line relay M is energized, the magnet D^{20} has its circuit completed and drawing down the arm d^{20} , the clutch z^{16} engages the constantly rotating clutch, thereby causing the spindle z^{20} carrying the wipers to rotate until an idle trunk is reached. When a trunk is idle its 45

multiple wire leading to the contact z^{60} is connected directly to battery through the normally closed contacts of the relay D. This relay when idle is, of course, deenergized and when busy is energized and battery is disconnected from the test contact z^{60} . When this trunk is busy, the difference of potential at contacts z^{60} is such that a test wiper z^{30} on any other switch in passing over one of them will not cause its cut-off relay M' to be operated. To make this clear I will describe the method of operation which is as follows: the subscriber, removing his receiver, closes the circuit of the relay M which, attracting its armature, closes the circuit of the magnet D^{20} causing the switch to rotate. When the wiper z^{30} makes connection with a contact leading to an idle trunk, such as is shown in the accompanying drawing, the relay M' immediately gets direct current from battery B through the contacts d^4 and d^5 . The energizing of the relay M' by this path disconnects the relay M and connects the line wires 1 and 2 to the extensions 3 and 4 respectively, and as soon as this happens, the relays D and D' become energized through the subscriber's station. The relay D is provided with a set of make before break contacts and upon operating, disconnects direct battery from the relay M' by here breaking the contacts d^4 and d^5 , but at the same time it closes the contacts d^6 and d^7 . The resistance coil I' is connected to battery and to the contact d^8 , and the relay M' is thereafter held energized by current flowing through this coil. It of course follows that the test wiper of any other switch in passing over this contact z^{60} will not operate its associate cut-off relay. The balance of the circuit and the operation of the same is identical to that shown in Fig. 1 and need not be described.

Referring now to Fig. 5, I have shown a switch connected to each line as in Fig. 4, but instead of having the secondary switch connected to a secondary outfit, I have it connected to the talking trunk. In this case when ground is connected to the starting wire 18 by the relay D' the circuit of the magnet D^{20} is closed, and upon operating draws down the arm d^{30} causing the switch to rotate. When the wiper z^{55} finds an idle secondary outfit (which would have battery connected to the contact z^{50} through the relay T) the relays S and T will be connected in series and the relay S operating the relay E in the same manner as in Fig. 1 disconnects ground from the starting wire 18 thereby opening the circuit of the magnet D^{20} causing the switch to come to rest. The balance of the circuit and operation is identical with that of Fig. 1 and need not be described here. These two Figs. 4 and 5 are simply modifications of Fig. 1, Fig. 1 being the preferred form. These various

modifications are shown so as to fully cover the different methods of connecting a calling line to a talking trunk and thereafter connecting the talking trunk to a secondary outfit for the purpose of completing the connection through switching mechanism on the calling end of the talking trunk.

I will now describe the complete operation tracing a connection from the calling to the called subscriber, assuming that subscriber A in Fig. 1 is the calling subscriber. When he takes down his receiver, line circuit 1 and 2 is closed and the relay M is energized. The energizing of this relay places battery on the contact z^{60} through the closing of the contacts m and m' . When the test wiper z^{30} of the normally revolving switch Z reaches this contact, the circuit of the magnet D^{20} is closed through the contacts d^3 and d^4 of the relay D and at the same time the circuit of the relay D^{10} is closed in multiple with this magnet. The energizing of the magnet D^{20} draws down the arm d^{30} separating the two clutches z^{15} and z^{16} causing the spindle z^{20} carrying the wipers z^{35} , z^{40} and z^{50} to come to rest. The energizing of the relay D^{10} closes the contacts d^{11} and d^{12} and d^8 and d^9 thereby connecting the trunk onto the line extensions 3 and 4. The relays D' and M' are thus placed in series and the energizing of the relay M' disconnects the relay M and removes battery from the test contact z^{60} . As soon as the relay M' is operated, the relay D becomes energized through the subscriber's station and attracting its armature maintains the circuit of the magnet D^{20} and relay D^{10} through the contacts d^2 and d^3 . The energizing of the relay D' places ground on the starting wire 18 and contact z^{35} through the normally closed contacts e and e' of the relay E. The wiper z^{35} of the normally revolving switch Z' on reaching this contact closes the circuit of the magnet D^{20} . The energizing of this magnet draws down the arm of d^{30} causing the spindle carrying the wipers to come to rest with the wipers on contacts leading to the calling trunk. The first thing that happens is that relay T is connected in series with the relay S by the following path: battery B, 29, 42, h^9 , h^{10} , 41, T, t^2 , t' , 40, armature and contact of relay D^{40} , z^{55} , z^{50} , 32, S to ground. The relay T becoming energized locks itself through the contacts t and t^2 and opening the contacts t' and t^2 removing itself from the wire 40 so as not to interfere with impulses that are to be transmitted over this wire. The relay S being momentarily energized, attracts its armature and closes the circuit of the relay E by the following path: battery B, 28, 21, s , s' , 20, E, 15, d^8 , d^9 to ground. The relay E thereupon locks itself through the contacts e^4 and e^5 as the contact e^4 is connected to the winding while the

contact e^2 is connected to battery. The operation of this relay disconnects the starting wire 18. The energizing of the relay T closes the circuit of the lamp L causing it to glow. The operator perceiving the signal, depresses the listening button k^2 connecting her talking set on wires 49-50 across the wires 32 and 33 through wires 40-39 and wipers z^{50} and z^{49} . The talking set being bridged across the wires 32 and 33, closes the circuit of the relays S and S' thus connecting the talking set to the trunk wires through the contacts s^2 , s^3 , s^7 and s^8 respectively. These two relays supply the operator's set with battery current and at the same time connect the set across the trunk wires enabling her to converse with the calling subscriber. The action of these relays at this time places battery on both trunk wires 30 ^{2} and 31 ^{2} through the contacts s^4 and s^6 and s^9 and s^{10} respectively. Battery current going over both sides of the trunk at the same time restores the switching mechanism in case it had been left in an unrestored position when the trunk was last used. The operator now being connected to the calling subscriber and asking for the number depresses the buttons of her key set corresponding to the number desired.

For illustration, suppose the number asked for was 43-3, the first two digits representing the telephone number and the last digit representing the signaling number as I wish to illustrate the manner of selective party-line ringing. The operator depresses the fourth key in the set K' , the third key in the set K^2 , and the third key in the set K^2 . Having thus set up the number the operator restores her listening key K^2 and closes the starting key K^2 thereupon closing the circuit of the relay H, Fig. 1, by the following path: battery B, 210, 82, H to ground. The energizing of this relay closes the circuit of the relay H' by the following path: battery B, 29, h^2 , h^2 , H' to ground. The energizing of the relay H' opens the locking circuit of the relay T but the circuit is maintained through the contacts h^2 and h^2 of the relay H' . The action of the relay H' closes the circuit of the motor M, Fig. 2 through the contacts h^2 and h^2 the arrow points indicating a source of power. Referring now to Fig. 2 the starting of the motor N causes the impulse wheels to rotate. At the first movement of the wheels, the pen q^2 rides on the metal portion of the wheel Q^{20} , thus maintaining the circuit of the motor N, after the starting button is released. The common wire 79 receives the vertical impulses, that is to say, impulses from the wheels Q^2 , Q^3 , Q^8 , Q^4 , etc., and from this wire the impulses are conveyed to the relay S through the path 79, 83, 40, contacts of D^{40} , z^{50} , z^{49} , 32, S, earth.

The rotary impulses, or the impulses from the wheel Q are conveyed to the relay S' through the path Q , g , 84, 39, z^{45} , z^{46} , 33, S' , 28, B. The first set of impulses to be received by the relay S are those transmitted from the pen q^2 of the wheel Q^2 . These impulses pass through the contacts of the fourth button of the set K' . The next impulse is a rotary impulse sent to the relay S' by the wheel Q . The second set of vertical impulses are sent to the relay S by the pen q^2 of the wheel Q^2 through the contacts of the third button of the set K^2 , then follows another rotary impulse from the wheel Q . The third set of impulses are sent from the pen q^2 of the wheel Q^2 through the contact of the third button of the set K^2 , then follows the third rotary impulse. After the last set of impulses, or after one complete revolution, the pen q^2 of the wheel Q^{20} rests on the insulated portion and the relay H becomes deenergized. The deenergizing of this relay opens the locking circuits of the relay T, thereby disconnecting the secondary set from the talking trunk. The deenergizing of the relay H releases the relay H' and extinguishes the lamp L. It, of course follows, that as the operator's talking set is connected to the secondary set and the secondary set is disconnected from the talking trunk the operator is prevented listening in on the trunk during conversation. The secondary set is only connected to the talking trunk while the number is being taken, and while the impulses are being sent. Referring now to Fig. 3 I will show how these impulses from the secondary set wheel operate the relays S and S' in Fig. 1 control the switching mechanism in this figure. I have already shown how the calling subscriber is automatically connected to a secondary set through a talking trunk, the secondary set simply containing the operator's set and impulse transmitter. I have also shown how these impulses from the various wheels affect the relays S and S' . The first set of impulses which, in this case number four causes the relay S to attract its armature four times and send that number of impulses over the wire 30 ^{2} through the contacts v^2 and v^2 . These impulses coming in over what is known as the vertical side of the trunk operate the vertical relay V which in turn closes the circuit of the vertical magnet V^2 , by the following path: ground v^2 , v^2 , u , u' , 203, switch arm v^{50} , 321, V^2 , 309, to battery B. The operation of this magnet causes the spindle Z carrying the wipers z and z' to step up vertically opposite a row of contacts corresponding to the number of impulses sent from the secondary set. After this first set of impulses a rotary impulse is placed on the wire 31 ^{2} or the rotary side of the trunk by the action of the relay S' . This impulse operates the relay V', which in turn closes the circuit of the private relay U through the path 31 ^{2} , v^{50} , 321, V' , 309, to battery B.

which causes the side switch to move one step, placing the various arms, w^{50} , w^{60} , w^{70} , and w^{80} on the second contacts. The movement of the arm w^{50} disconnects the vertical magnet V^2 and in its place connects the rotary magnet V^3 , while the operation of the arm w^{80} connects or places the test relay J' in position to test the tip side of the line. The second set of impulses numbering three, 10 operates the relay V which in turn closes the circuit of the rotary magnet V^2 causing the spindle Z to rotate and bring the wipers to rest on contacts leading to the desired line. The second rotary impulse now coming in 15 operates the relay V' which closes the circuit of the private relay U causing the side switch to take another step bringing the switch arms to rest on the third contacts. During this second rotary impulse while the 20 relay U is energized the test relay J' is connected directly to the tip side of the line and if the line were busy the relay J' would become energized and closing the circuit of the release magnet J restore the switch to its 25 normal position. We will take it for granted that the called line is idle, so therefore the switch arms rest on their respective contacts. The switch arm w^{50} disconnects the rotary magnet V^3 and in its place connects 30 the relay R' . The switch arms w^{60} and w^{70} close their respective trunk circuits while the switch arm w^{80} disconnects the test relay from the tip side of the line or trunk. The calling subscriber is now connected to line 35 number 43. The third set of impulses now coming in operate the relay V which in turn closes the circuit of the relay R' . The first one of these impulses affecting this relay causes it to close the circuit of the relay X' 40 by the following path: ground, p^2 , p^3 , X' , 320, p' , p , 309, to battery B. This relay now locks itself through the contact x , the contact x being connected to ground through the springs z^2 and z^3 which are controlled 45 by the switch spindle. The winding of the relay X' is connected to battery through the normally closed contacts k , k' of the relay R . Battery is now placed on the locking contacts of the ringing relay set W through the 50 common wire 150 and the contacts x^2 and x^3 of the relay X' . The number of impulses in this last set are three which correspond to the ringing number of the desired party. 55 The first impulse affecting the relay R' does not affect any of the relays in the ringing set W , but immediately after the first impulse when the relay R' drops back the circuit of the relay W^4 is closed by the following path: battery B, 309, x^3 , x^2 , p^6 , p^7 , 60 315, w' , w^2 , w^4 , to ground. The second impulse coming in operating the relay R' closes the circuit of the relay W^5 by the following path: battery B, 309, x^3 , x^2 , p^6 , p^5 , 65 314, w^6 , w^5 , w^{13} , w^{14} , W^5 to ground. The operation of the relay W^5 disconnects the first 70 generator G' and connects the generator G^2 in its place to the normally open contact in the ringing relay Y . Immediately after the second impulse the relay R' dropping back closes the circuit of the relay W^6 through the path already described to wire 315 and from there through w' , w , w^8 , w^9 , W^6 , to ground. The third impulse coming in closes the circuit of the relay W^7 through the path already described to wire 314 and from there 75 through w^6 , w^5 , w^{13} , w^{12} , w^{21} , w^{22} , W^7 , to ground. The operation of the relay W^7 disconnects generator G^3 which is of proper frequency or polarity to ring the bell at the 80 desired station. Immediately after the third impulse the circuit of the relay W^8 is closed in a manner similar to that already described in connection with the other relays. The proper generator current is now 85 placed on the contacts in the ringing relay Y . One terminal of the relay Y is connected directly to an interrupting machine Y' and the interrupting machine itself is connected directly to battery. The other terminal of the relay is connected to ground through the normally closed contacts p^1 and p^2 of the relay R' in series with the contacts x^4 and x^5 of the relay X' . While the 90 ringing impulses are being sent and the proper relay in the ringing set W is being selected the relay Y is not affected on account of the rapid making and breaking of the contacts p^1 and p^2 . After the impulses have been sent and the relay R' is in its 95 normal position the circuit of the relay Y is closed and opened through the interrupting machine Y' . When its circuit is closed the relay Y opens the trunk and places generator current on the calling end of the trunk. 100 This current is placed on the line intermittently and during one of these intermissions when the relay Y is deenergized and the called subscriber removes his telephone the relay R becomes energized and opening the contacts p and p' releases the relay X' which in turn opens the circuit of the ringing relay Y , thus preventing any further generator current being placed on the line. The retardation, or resistance coil $1'$ is provided to hold up the cut-off relay of the line while 105 generator current is being sent over the line. 110 From the foregoing description it will be seen that the two subscribers are provided with a clear talking circuit, battery being supplied to the called subscriber from the connector switch and battery supplied to the calling subscriber from the trunk. In this present arrangement there are two sets of 115 condensers in this talking circuit and also an additional bridge caused by the relays V and V' which are not needed at this junction. The relay X' which is released when the called subscriber answers also unlocks the relays in the ringing set W thus prevent- 120

ing a waste of current. At the end of the conversation the calling subscriber hanging up his telephone deenergizes the relay D and this relay dropping back releases the relay 5 D' which upon falling back opens the trunk circuit disconnecting the relay D' and the line cut-off relay M'. The relay D being the first to fall back places battery on both sides of the trunk leading to the switching mechanism through the contacts e⁵, e⁶, and e⁷, e⁸. The relay D' is the next relay to drop back thereby releasing the relay E, removing the battery from both sides of the trunk. From this combination it will be seen that a momentary impulse has been placed simultaneously on both trunk wires. Referring now to Fig. 3 this momentary impulse operates the relays V and V' closing the circuit of the relay J' by the following path: ground 10 v, v', J', battery B. This latter relay operating closes the contacts j and j' energizing the release magnet J thereby restoring the switch to its normal position.

By the term "continuously rotated" as applied to the switching means in the appended claims, is meant switches having either or both of the following characteristics: (1) a uniform motion of revolution of their wipers about the axis of the spindle as distinguished from a step-by-step movement about the same axis, and irrespective of whether the said uniform movement be continued for the period of the testing operation only or sustained for an indefinite period; (2) a switching device rotated by a step-by-step motion or otherwise always in the same angular direction, the said switch having no normal or zero position and consequently no release device for returning it 40 to that position.

I do not herein claim tri-headed trunks or secondary distributing means to operators' controlling devices basically or generically, inasmuch as the basis and generic claims to this subject matter are made in copending applications of mine disclosing other species of my invention and the serial numbers and filing dates of which are as follows: Serial No. 369,201, filed April 20, 45 1907; Serial No. 383,874, filed July 15, 1907, and Serial No. 383,875, filed July 15, 1907.

Having thus described my invention, what I claim and desire to secure by Letters 55 Patent is:

1. In a telephone exchange system, a plurality of line circuits, a plurality of link circuits for interconnecting the same, a double set of automatic switches associated 60 with said links, one set adapted to effect initial connection between links and lines, and the other set to be driven in a predetermined manner to the wanted lines, mechanism adapted to be controlled by an 65 operator for directing the second set of

switches, and a continuously rotated secondary switch individual to said operator's mechanism arranged to be automatically driven to connect its associated operator's mechanism with the link circuit associated with the calling line and thereby associate 70 said operator's mechanism with the switches of the second set for the operator's control thereof.

2. In a telephone exchange system, a plurality of line circuits, a plurality of connecting trunks, automatic switches for connecting the same to calling lines, other automatic switches for connecting the same to wanted lines, means for actuating said last mentioned automatic switches comprising operator's number selecting circuit closers and a power driven impulse generator therefor at a central point, and a continuously rotated secondary switch individual to said operator's selecting set, and active upon connection of any trunk to a calling line to feed the trunk and connect the associated operator's set thereto, substantially as described. 75 80 85

3. In a telephone exchange system, a plurality of subscribers' lines, a plurality of connective link circuits, a double set of automatic switches for said links, the first set adapted to connect calling lines thereto, and the second set to connect the links with wanted lines, an operator's set comprising a telephone and mechanism adapted to actuate the second set of switches, and an auxiliary continuously rotated switch individual to each operator's set and automatically actuated when a line is calling to connect the operator's set through a link circuit to a calling subscriber and also to the second set of switches, whereby the wanted subscriber may be selected, substantially as described. 90 95 100 105

4. In a telephone exchange system, a plurality of line circuits and a plurality of trunk lines less in number than the line circuits, automatic switches for connecting calling lines to said trunks, and other automatic switches for connecting the trunks to wanted lines, together with operators' controlling apparatus for the trunks, and automatic continuously rotated switches, one individual to each set of operator's controlling apparatus for connecting the operator's sets to the trunks, substantially as described. 110 115 120

5. In a telephone exchange system, a plurality of line circuits, a plurality of connective trunks therefor less in number than the number of lines, a primary selector switch for each trunk adapted 125 to connect the trunk with a calling line, a selector switch constituting the connecting or calling terminal of the trunk, an operator's answering and controlling set, and a continuously rotated secondary set. 130

lector switch individual to said operator's set for connecting the same to the trunk, substantially as described.

6. In a telephone exchange system, a plurality of line circuits, a number of trunks less than the number of lines, automatic switches for connecting calling lines with the trunks, automatic switches for connecting the trunks with wanted lines, operators' impulse transmitting apparatus and telephone sets, continuously rotated secondary selector switches, one individual to each operator's set for connecting the operator's devices with the trunks, and switches controlled by operators for connecting the impulse transmitter to said trunks, substantially as described.

7. In a telephone system, a plurality of line circuits; a plurality of connecting links; normally continuously driven automatic switches for connecting said links to calling lines; other automatic switches for connecting said links to wanted lines; operator's answering and controlling devices adapted to determine the operation of the second set of automatic switches, and auxiliary automatic switches for connecting said links to said operator's answering and controlling devices, substantially as described.

8. In a telephone system, a plurality of line circuits; a plurality of connecting links; normally continuously driven automatic switches for connecting said links to calling lines; other automatic switches for connecting said links to wanted lines; operator's answering and controlling devices adapted to determine the operation of the second set of automatic switches, and mechanically driven auxiliary automatic switches for connecting said links to the operator's answering and controlling devices, substantially as described.

9. In a telephone system, a plurality of line circuits; a plurality of connecting trunks; normally continuously driven automatic switches for connecting trunks to calling lines; automatic selective switching devices for connecting trunks to wanted lines; means controlled by an operator for actuating said selecting devices; and automatic switching devices for connecting said operator-controlled means to a trunk upon said trunk's being connected to a calling line, substantially as described.

10. In a telephone system, a plurality of line circuits; a plurality of connecting trunks; normally continuously driven automatic switches for connecting trunks to calling lines; automatic selective switching devices for connecting trunks to wanted lines; means controlled by an operator for actuating said selecting devices; and power-driven automatic switching devices for connecting said operator-controlled means to a trunk

upon said trunk's being connected to a calling line, substantially as described.

11. In a telephone system, a plurality of lines, a plurality of interconnecting links therefor, means for connecting a calling line to one of said links, selective switching means for connecting a link with a wanted line, a plurality of operators' sets comprising telephones and actuating devices for said selective switching means, and normally continuously driven automatic mechanism adapted upon connection of a link with a calling line to be automatically actuated so as to connect said link and its switching mechanism with an idle operator's set, substantially as described.

12. In a telephone system, a plurality of lines; a plurality of links; a plurality of operator's controlling devices normally disconnected from the links but associated therewith; means for connecting a calling line to one of said links; normally continuously driven automatic means for causing said link to connect with an idle one of said operator's controlling devices when said link becomes connected with a calling line; and means responsive to said operator's controlling device for connecting said links with desired lines, substantially as described.

13. In a telephone system, a plurality of lines; a plurality of links for interconnecting said lines; normally continuously and mechanically driven automatic switches for connecting one of said lines that originates a call with an idle one of said links; a plurality of operator's controlling mechanisms; auxiliary automatic switches for enabling a link so chosen to be selected and connected with an idle one of said controlling mechanisms, and means responsive to said controlling mechanisms for selecting a wanted line and connecting said link thereto, substantially as described.

14. In a telephone system, a plurality of lines; a plurality of links for interconnecting said lines; normally continuously and mechanically driven automatic switches for connecting one of said lines that originates a call with an idle one of said links; a plurality of operator's controlling mechanisms normally disconnected from said links; auxiliary automatic switches, one individual to each operator's control mechanism, for enabling a link so chosen to be selected and connected with an idle one of said controlling mechanisms; and switching devices associated with said links, responsive to said controlling mechanisms for connecting said links to wanted lines, substantially as described.

15. In a telephone system, telephone lines; trunks; automatic switches; each trunk terminating in the wipers of an automatic switch, the said lines being multiplied through a plurality of said automatic

- switches and appearing as waiting contacts in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the 5 trunk; a source of continuous power; a clutch connecting said source of continuous power and the wiper shaft of the automatic switch of the trunk; and an electromagnet having its armature associated with the said 10 clutch and having its helix associated with the said auxiliary conductor of the trunk, whereby the clutch may be operated by the engagement of the wiper of the auxiliary trunk conductor with a calling terminal of 15 the line auxiliary conductor.
16. In a telephone system, telephone lines; trunks; automatic switches; each trunk terminating in the wipers of an automatic switch, the said lines being multiplied through 20 a plurality of said automatic switches and appearing as waiting contacts in said automatic switches and each of said automatic switches having a wiper shaft carrying the wipers of that switch; an auxiliary 25 conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said 30 auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said auxiliary conductor of the trunk whereby the electromagnet may be operated 35 to control the clutch by closure of proper circuit from the wiper of the trunk's said auxiliary conductor; and means for continuing the operation of said electromagnet dependently upon the continuance of the calling condition upon the telephone line then associated with the trunk through the wipers and contacts of the automatic switch, substantially as described.
18. In a telephone system, telephone lines; trunks; automatic switches; each trunk terminating in the wipers of an automatic switch, the said lines being multiplied through a plurality of said automatic switches and appearing as waiting contacts in said automatic switches, and each of said automatic 40 switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said auxiliary conductor of the trunk whereby the electromagnet may be operated 45 to control the clutch by closure of proper circuit from the wiper of the trunk's said auxiliary conductor; and means for continuing the operation of said electromagnet dependently upon the continuance of the calling condition upon the telephone line then associated with the trunk through the wipers and contacts of the automatic switch, substantially as described.
19. In a telephone system, telephone lines; trunks; automatic switches; each trunk terminating in the wipers of an automatic switch, the said lines being multiplied through a plurality of said automatic switches and appearing as waiting contacts 50 in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said auxiliary conductor of the trunk whereby the electromagnet may be operated 55 to control the clutch by closure of proper circuit from the wiper of the trunk's said auxiliary conductor; and means for continuing the operation of said electromagnet dependently upon the continuance of the calling condition upon the telephone line then associated with the trunk through the wipers and contacts of the automatic switch, substantially as described.
20. In a telephone system, telephone lines; trunks; automatic switches; each trunk terminating in the wipers of an automatic switch, the said lines being multiplied through a plurality of said automatic switches and appearing as waiting contacts 60 in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said auxiliary conductor of the trunk whereby the electromagnet may be operated 65 to control the clutch by closure of proper circuit from the wiper of the trunk's said auxiliary conductor; and means for continuing the operation of said electromagnet dependently upon the continuance of the calling condition upon the telephone line then associated with the trunk through the wipers and contacts of the automatic switch, substantially as described.

- trunk; means whereby said electromagnet may be energized when said auxiliary conductor makes electrical connection through its wiper with the waiting contact of the auxiliary conductor of a calling line; and means for continuing the energization of said electromagnet independently of the circuit which initiated such energization, substantially as described.
20. In a telephone system; telephone lines; trunks; automatic switches; each trunk terminating in the wipers of an automatic switch, the said lines being multiplied through a plurality of said automatic switches and appearing as waiting contacts in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said clutch and having its helix in circuit with the said auxiliary conductor of the trunk; means whereby said electromagnet may be energized when said auxiliary conductor makes electrical connection through its wiper with the waiting contact of the auxiliary conductor of a calling line; and a relay associated with said trunk and adapted to continue the energization of said electromagnet independently of the means for energizing first mentioned, substantially as described.
21. In a telephone system; telephone lines; trunks; automatic switches; each trunk terminating in the wipers of an automatic switch, the said lines being multiplied through a plurality of said automatic switches and appearing as waiting contacts in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said clutch and having its helix in circuit with the said auxiliary conductor of the trunk; means whereby said electromagnet may be energized when said auxiliary conductor makes electrical connection through its wiper with the waiting contact of the auxiliary conductor of a calling line; means for removing from the waiting contact of the auxiliary line conductor the electrical condition resulting in the energization of said electromagnet; and other means for continuing the energization of said electromagnet independently upon the continuance of the calling condition upon the telephone line then associated with the trunk through the wipers and contacts of the automatic switch, substantially as described.
22. In a telephone system, telephone lines; trunks; automatic switches; each trunk terminating in the wipers of an automatic switch; the said lines being multiplied through a plurality of said automatic switches and appearing as waiting contacts in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; a clutch connecting said source of continuous power and the wiper shaft of the automatic switch of the trunk; an electromagnet having its armature associated with the said clutch and having its helix in circuit with the said auxiliary conductor of the trunk; means for removing from the waiting contact of the auxiliary line conductor the electrical condition resulting in the energization of said electromagnet; and other means for continuing the energization of said electromagnet subsequently to the change of the condition causing initial energization, substantially as described.
23. In a telephone system; an automatic switch having movable wipers and fixed waiting contacts as parts thereof; a telephone line having speech-circuit conductors and an auxiliary conductor terminating in waiting contacts of said switch; a connective link circuit terminating in wipers of said switch; a source of power; a clutch adapted to connect said source of power to said wipers and wherethrough said wipers may be continuously driven; an electromagnet controlling said clutch to disassociate said source of power from said wipers; a source of current; a conductive path extending from one terminal of said source of current through said electromagnet and to a wiper in said switch making connection at intervals with the auxiliary conductor of said line; and a conductive path extending

- from the other terminal of said source of current to the auxiliary conductor of said line when said line is calling, said two conductive paths being connected when the link 5 wipers are in connection with the waiting contacts of the line when calling whereby said electromagnet may be operated to control said clutch to stop the wipers upon the contacts of said line when calling, substantially 10 as described.
24. In a telephone system; an automatic switch having movable wipers and fixed waiting contacts as parts thereof; a telephone line having speech-circuit conductors 15 and an auxiliary conductor terminating in waiting contacts of said switch; a connective link circuit terminating in wipers of said switch; a source of power; a clutch adapted to connect said source of power to said wipers 20 and wherethrough said wipers may be continuously driven; an electromagnet controlling said clutch to disassociate said source of power from said wipers; a source of current; a conductive path extending from one 25 terminal of said source of current through said electromagnet and to a wiper in said switch making connection at intervals with the auxiliary conductor of said line; a conductive path extending from the other terminal 30 of said source of current to the auxiliary conductor of said line when said line is calling, said two conductive paths being connected when the link wipers are in connection with the waiting contacts of the line 35 when calling whereby said electromagnet may be operated to control said clutch to stop the wipers upon the contacts of said line when calling; a cut-off relay associated with said line and controlling the current path from 40 the source of current to the auxiliary conductor of said line, said path being interrupted as a consequence of the energization of said cut-off relay; and a relay associated with said link and adapted to control the 45 energization of said electromagnet subsequently to the operation of said cut-off relay, substantially as described.
25. In a telephone system; an automatic switch having movable wipers and fixed 50 waiting contacts as parts thereof; a telephone line having speech-circuit conductors and an auxiliary conductor terminating in waiting contacts of said switch; a connective trunk circuit terminating in wipers of said switch; a source of power; a clutch adapted to connect said source of power to said wipers and wherethrough said wipers may be continuously driven; an electromagnet 55 controlling said clutch to disassociate said source of power from said wipers; a source of current; a conductive path extending from one terminal of said source of current through said electromagnet and to a wiper 60 in said switch making connection at intervals with the auxiliary conductor of said 65 line; a conductive path extending from the other terminal of said source of current to the auxiliary conductor of said line when said line is calling, said two conductive paths being connected when the link wipers are 70 in connection with the waiting contacts of the line when calling whereby said electromagnet may be operated to control said clutch to stop the wipers upon the contacts of said line when calling; a cut-off relay 75 associated with said line and controlling the current path from the source of current to the auxiliary conductor of said line, said path being interrupted as a consequence of the energization of said cut-off relay; and 80 means for controlling the energization of said electromagnet after the operation of said cut-off relay, substantially as described.
26. In a telephone system; an automatic primary selector switch; an automatic continuously rotated secondary selector switch; a line appearing in waiting contacts of said primary selector switch; a link appearing in wipers of said primary selector switch and 85 in waiting contacts of said secondary selector switch; means for stopping the wipers of said primary selector switch in electrical connection with a calling line; means for stopping the wipers of said secondary selector switch in electrical connection with the waiting contacts of said link when primarily connected with said line, selective 90 means adapted to connect the link with wanted lines, and an operator's set associated with said secondary selector switch and 95 comprising a telephone and actuating means for said line selecting means, substantially as described.
27. In a telephone system; an automatic primary selector switch; an automatic continuously rotated secondary selector switch; a line appearing in waiting contacts of said primary selector switch; a trunk appearing in wipers of said primary selector switch and in waiting contacts of said secondary selector switch; a source of current; a relay associated with said line and adapted to 100 connect one terminal of said source of current to the test terminal of said line in said primary selector switch; and a relay associated with said trunk and adapted to connect one side of said source of current to the test terminal of said trunk in said secondary selector switch, said relay associated with said trunk being energized when said trunk is connected through said primary selector switch with a calling line, substantially as described.
28. In a telephone system; lines; an automatic primary selector switch; a trunk; 105 means for connecting said trunk through said automatic primary selector switch to a calling one of said lines; an automatic continuously rotated secondary selector switch, having waiting contacts connected with said 110 lines.

trunk; a source of current; and a relay associated with said trunk and operated upon connection of said trunk with a calling line, adapted to complete a path from a waiting 5 contact in said secondary selector switch to one terminal of said source of current; and means whereby the wipers of said secondary selector switch may be stopped in connection with the trunk when said relay is operated, substantially as described.

29. In a telephone exchange system, a plurality of lines to be interconnected, a plurality of automatic switches for effecting the interconnection, but normally disconnected 15 from said lines, continuously rotated switches for connecting the said automatic switches to calling lines, and an operator's sender for controlling said automatic switches, said sender comprising a key board 20 having keys or buttons arranged in groups corresponding to the digits of the numbers to be called, and means for connecting said sender to any of said automatic switches.

30. In a telephone exchange system, a plurality of lines to be interconnected, a number 25 of trunk circuits less than the number of lines, automatic switches adapted to connect said trunk circuits to called lines, a plurality of operators' senders for controlling said 30 automatic switches, said senders being less than the number of trunks, a normally continuously rotating switch for connecting each trunk with a calling line and means for connecting the said senders to the trunks.

31. In a telephone exchange system, a plurality of lines to be interconnected, a number 35 of trunk circuits less than the number of lines, automatic switches for connecting said trunk circuits with called subscribers' lines, an operator's sender for controlling said 40 automatic switches, normally continuously rotating switches for connecting the trunk to calling lines and means to connect said sender to said trunk circuits.

45. 32. In a telephone exchange system, a plu-

rality of lines to be interconnected, a plurality of automatic switches for effecting the interconnection, but normally disconnected from said lines, normally continually rotating switches for connecting the said automatic switches to calling lines, and an operator's sender for controlling said automatic switches, said sender comprising a key board having keys or buttons arranged in groups corresponding to the digits of the numbers 50 to be called, and means for connecting said sender to any of said automatic switches.

33. In a telephone exchange system, a plurality of lines to be interconnected, a number of trunk circuits less than the number of 60 lines, automatic switches adapted to connect said trunk circuits to called lines, a plurality of operators' senders for controlling said automatic switches, a continuously rotated switch, per trunk, controlled by the receiver 65 hooks at the subscriber's station for connecting the trunks with the calling lines and means for connecting the said senders to the trunks.

34. In a telephone exchange system, a plurality of lines to be interconnected, a plurality of automatic switches for effecting the interconnection, but normally disconnected from said lines, continuously rotated switches controlled by the subscriber's receiver 70 hooks for connecting the said automatic switches to calling lines, and an operator's sender for controlling said automatic switches, said sender comprising a key board having keys or buttons arranged in groups 75 corresponding to the digits of the numbers to be called, and means to connect said sender to any of said automatic switches.

In testimony whereof I affix my signature in presence of two witnesses.

EDWARD E. CLEMENT.

Correction in Letters Patent No. 1,109,618

It is hereby certified that in Letters Patent No. 1,109,618, granted September 1, 1914, upon the application of Edward E. Clement, of Washington, District of Columbia, for an improvement in "Telephone-Exchange Systems," an error appears in the printed specification requiring correction as follows: Page 8, strike out lines 41-52, and insert the following paragraph:

I do not claim broadly herein the fundamental features of the system disclosed, including primary and secondary distributing means, as such, broad claims to this subject matter and to the several other matters disclosed but not claimed herein, being contained in my copending application serial No. 858,481, filed August 25, 1914, as a continuation in part of serial No. 323,096, filed June 23, 1906. Related claims are also contained in other copending applications as follows: Serial Nos. 369,201, filed April 20, 1907; 383,874, filed July 15, 1907; and 383,875, filed July 15, 1907; and that the said Letters Patent should be read with this correction therein that the same may conform to the record of the case in the Patent Office.

Signed and sealed this 22nd day of September, A. D., 1914.

[SEAL.]

R. F. WHITEHEAD,
Acting Commissioner of Patents.
